Attorney

UNITED STATES PATENT OFFICE.

GEORGE F. KRENGEL, OF FRANKFORT, INDIANA.

CHICKEN-ROOST HANGER.

Application filed November 9, 1926. Serial No. 147,284.

My said invention relates to a hanger for supporting a chicken or poultry roost and it is an object of the invention to provide a simple and inexpensive roost hanger having means for preventing insects such as mites or the like from getting on the roost from the wall of the house in which the roost is mounted.

Referring to the accompanying drawings which are made a part hereof and on which similar reference characters indicate similar parts,

Figure 1 is a side elevation illustrating the application of my invention, and

Figure 2 is a similar enlarged fragmentary detail view.

In the drawings reference character 10 indicates the upright sides of a chicken house or coop, 11 a roost and 12 a hanger or bracket for supporting the same.

The hanger or bracket 12 comprises a substantially flat base, one of which may be attached by wood screws 13 or the like to each side of the chicken coop and said flat base is provided with an upstanding boss or lug having one end provided with an opening forming a cup 14 and a central depression 15 for the reception of the extremity of a supporting wire 16. The supporting wire 16 is curved in substantially U-shape and is disposed in inverted position with one end extending downwardly a greater distance and bent to receive the end of the perch or roost 11. The lower roost engaging end of the wire 16 is bent at right angles to its body then upwardly and inwardly at a slight angle, thence rearwardly parallel to the right-angular portion and with its free end extending downwardly and inwardly therefrom. The cup 14 is adapted to be filled with oil to prevent mites which get on the floor and side walls of the chicken coop or house from crawling onto the perch or roost 11 and along the wire 16. Since the depending portion of the wire 16 which supports the roost is spaced from the bracket 12 chickens or other fowls will not be permitted to rub against the wall of the chicken house and therefore no mites or other pests

can reach the chickens when they are on the roost.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. The combination of a bracket, a recess provided in said bracket and forming an oil cup, a socket in the bottom of said recess, and a roost supporting element of substantially U-shape and having one end for engagement in said socket and its other end formed for supporting a roost, said roost supporting end comprising a pair of horizontal portions spaced longitudinally of the roost, substantially as set forth.

2. The combination with a bracket having a recess forming an oil cup and a socket in the bottom of the recess, of a roost supporting element having one end arranged to fit snugly in said socket and curving over and downwardly with its lower portion twisted to provide a non-circular portion to fit snugly about a roost for preventing the tilting of the same, substantially as set forth.

3. The combination with a bracket having a recess forming an oil cup and a socket in the bottom of the recess, of a roost supporting element having one end arranged to fit snugly in said socket and curving over and downwardly with its lower portion twisted to provide a non-circular portion to fit snugly about a roost for preventing the tilting of the same the twisted portion of the roost supporting element being disposed below said bracket and permitting the roost to swing, substantially as set forth.

In witness whereof, I have hereunto set my hand at Frankfort, Indiana, this 2nd day of November, A. D. nineteen hundred and twenty-six.

GEORGE F. KRENGEL.
